105,313

DESIGN FOR A CIGARETTE ASH RECEPTACLE

Paul L. Zesbaugh, Minneapolis, Minn.

Application April 8, 1937, Serial No. 68,632

Term of patent 14 years

To all whom it may concern:

Be it known that I, Paul L. Zesbaugh, a citizen of the United States and a resident of Minneapolis, in the county of Hennepin and State of Minnesota, have invented a new, original, and ornamental Design for a Cigarette Ash Receptacle, of which the following is a specification, reference being had to the accompanying drawing, forming part thereof.

Figure 1 is a perspective view; and

Figure 2 is a central vertical section of a cigarette ash receptacle showing my new design.

The design is characterized by a bowl provided with an upstanding unbroken rim, from one side of which there projects an outwardly extending pocket-like lug, the top of which lies substantially flush with the upper edge of the rim; the bowl being provided with a centrally disposed upstanding hub in the top portion of which there are formed supporting grooves or channels.

I claim:

The ornamental design for a cigarette ash receptacle as shown and described.

PAUL L. ZESBAUGH.
